AUTOMATIC TRAIN PIPE COUPLING HEAD

Joseph Robinson, New York, N. Y., assignor of
one-half to Roy M. Wolvin, Montreal, Quebec,
Canada

Application December 3, 1934, Serial No. 755,831

7 Claims. (Cl. 285—58)

My invention provides an improved coupling head for automatic train pipe connectors in which the maximum of gathering range is combined with the maximum compactness. This is 5 accomplished by a novel arrangement of guiding means which include a forwardly extending flaring guiding prong and inclined walls which converge to form a funnel, in association with a guiding pin or ball member that co-acts with 10 said inclined walls when opposing coupling heads couple under conditions of disalignment. A coupling head made in accordance with my invention will be relatively small and yet it will negotiate conditions of vertical disalignment in 15 recess of 12" and conditions of lateral disalignment in recess of 8".

Other advantages will appear in the following description and from the accompanying drawings in which

20 Figure 1 is a front elevation of my improved coupling head;

Figure 2 is a side elevation thereof;

Figure 3 is a rear elevation of my improvement;

25 Figure 4 is a plan view thereof;

Figure 5 is a vertical elevation of two of my improved coupling heads connected together, as seen from the rear of one thereof;

Figure 6 is a plan view of the base A of my 30 improved head showing a modification therein. In this view the guiding means are broken away; and

Figure 7 is a front elevation, on regular scale, of the base A of my improvement illustrating a 35 further modification therein. In this view the guiding means are also broken away.

Any suitable means may be employed to yieldingly support my improved coupling head from the car coupler or from the car itself. In my 40 co-pending application filed November 26, 1934, Serial No. 754,889, an efficient form of support for this purpose is shown and described. The flat vertically disposed generally oblong base A of my improvement is provided on its vertical center

45 line with a sleeve or shank 1 having an opening 2 therethrough to receive the support. Normally a gasket is suitably mounted in the opening with its front face lying approximately in the plane of the coupling face of my improved head. The base A is provided with a pair of forwardly ex- 50

tending, outwardly and vertically flaring wings or prongs B and C each of which is joined by the inclined converging walls 3 of a funnel guiding member D. The apex of the funnel lies behind 55 the base A and unites the walls 3 at the end of their rearward flare.

A portion of the outer edges 4 and 5 of the wings or prongs B and C lie generally in the vertical plane. From these points they turn in- 60

wardly and join or merge with the flaring walls 3 which comprise the funnel D. The outer edge 5 of the wing C joins the base A at or near the vertical center line of the latter, as shown at 6 in Figures 1 and 3, and conforms for a short lateral distance to the outline of the bottom of 5 the base A. This shape may also be given to the base 7 of the prong 4 if desired. Preferably I join this prong to the vertical side of the base A, and there end the base 7 of the prong, in order to permit additions to be made to the top 10 of the base A without preventing efficient interchange between my improved coupling head and a companion head not provided with the addition. The lower prong C may if desired be likewise arranged, or both prongs may be arranged 15 on the base A each alike.

At its edge 8 the base is turned or flared rearwardly to meet the walls 3 of the funnel D. Its opposite edges 9 are also flared or turned rearwardly. This may be accomplished either by a 20 radius at this point or the whole portions 10 of the base, above and below the horizontal center of the base, may be angled or inclined rearwardly, as shown in Figure 4. This arrangement has the effect of increasing the gathering range of my 25 improved head under certain conditions. A somewhat similar increase in gathering range can also be procured by removing the portions 10 entirely as shown in Figure 6.

The apex of the funnel D is provided on its 30 front face with a machined annular seat 11 which receives the blunt machined front face of the ball 12 of a mating coupling head, as shown in Figure 5. The ball is attached to or is formed integral with the outer end of a laterally and 35 forwardly extending vertically narrow hollow arm E formed integral with the base A or otherwise secured thereto. The ball and the seat 11 occupy the same horizontal plane, and both are spaced an equal distance laterally on opposite 40 sides of the vertical center line of the base or coupling head A. The arrangement is such that when mating heads couple, Figure 5, the ball 12 rests firmly in the seat of a mating head as afore- 45 said, a position of these parts which accurately aligns the openings 2 in the heads and holds the mated heads securely against disalignment while coupled. The seat 11 may if desired be formed of a plurality of inwardly extending lugs such as shown, and for the purpose stated, in my afore- 50 said co-pending application. Preferably the diameter of the ball 12 at its point of engagement with the seat is such as to avoid damage to the connector gasket if struck by the ball under any adverse condition of surface.

The raised surfaces 14 of the base A serve as bearing points for the top and bottom of connected heads and, with the seats 11 and balls 12, constitute a wide four point bearing contact or seat. The arrangement insures a rigid joint be- 55 60

tween mated heads when under the pressure of the buffer springs that formed a part of the head supporting means shown in my co-pending application mentioned.

- 5 The angle at which the arm E projects forwardly of the base A of the head enables its inner surface 15 to act, under certain conditions, as a third guiding prong similar in operation to the lateral gathering function of the prongs B and C.
- 10 Normally, however, this member guides the heads into alignment through contact of its ball 12 with the walls of the funnel D. Suitable reinforcing webs 16 are employed to strengthen my improved coupling head at different points.
- 15 In operating under extreme vertical displacements the lower part of the prong or wing C engages the under side of the arm E of a mating head and lifts the ball 12 into the path of the funnel D. Thereafter the funnel and the ball 20 (or arm E) do most or all of the aligning. If a coupling is being made under a condition of extreme lateral disalignment the lower edge 5 of the prong C will engage the similar portion of the counterpart prong of a mating head and 25 carry the ball 12 laterally into the path of the funnel D. Under some conditions of lateral disalignment this engagement occurs between the edges 4 of the upper prongs B of mating heads when such prongs project in front of the coupling 30 face of the heads. It will be understood however, that the length of the prongs, their lateral and vertical flare, and the distance of the seat 11 and the ball 12 laterally from the center line of the base A, must be such as to best suit the 35 service requirements to be imposed. The prong B may, for instance, terminate in the plane of the coupling face of the head A, or behind such plane, if desired. Similarly, the length of the arm E, and the angle of its surface 15, and the 40 distance from the front face of the base A rearwardly to the vertical plane occupied by the seat 11, must be adjusted to best suit the particular operating requirements involved. If desired, the edge 8 of the base may also be angled rearwardly 45 as at 10 in Figure 6, and the location as well as the shape and dimensions of the prongs B, C, and E may be changed to best suit the coupling requirements under consideration. They may, for instance, be shifted to the side of the base A 50 opposite to the side occupied by them in the accompanying drawings.

What I claim is:

1. An automatic train pipe coupling head 55 operating with a mating coupling head and comprising, in combination, a vertically disposed substantially flat base disposed normal to the longitudinal axis of the coupling head, a plurality of forwardly extending laterally diverging guiding prongs connected to said base, a rearwardly inclined funnel guiding member on said base, another guide member on said base, the last mentioned member traveling along one of said guiding prongs of a mating coupling head when opposing coupling heads couple under conditions of disalignment, whereby to guide said another guide member into the funnel guiding member of the mating head.
2. An automatic train pipe coupling head 60 operating with a mating coupling head and comprising, in combination, a base, a plurality of vertically spaced forwardly extending vertically flaring guiding members joined together by a fun-

nel member, interposed therebetween and all disposed on the same side of the vertical center of the head, the apex of said funnel member lying behind the base of said guiding members, and an arm on the base, the arms of mating coupling heads cooperating with the guide members for aligning said heads. 5

3. An automatic train pipe coupling head 10 operating with a mating coupling head and comprising, in combination, a base, a plurality of vertically spaced forwardly extending vertically flaring guiding members, one of which projects in advance of the other and has a greater vertical flare than the other, a funnel member uniting said guiding members throughout, and an 15 arm, the arms and guiding members of mating heads being adapted to cooperate for aligning said heads.

4. An automatic train pipe coupling head 20 operating with a mating coupling head and comprising in combination a base, a plurality of forwardly extending vertically flaring guides one of which projects in advance of said base to a greater extent than the other and is connected to said base at a point nearer the vertical center line of 25 the base, guide means adjacent said flaring guides and a receptacle for said guide means, which receptacle lies between said guides, the guide means and said guides of mating coupling heads being adapted to align the latter with respect to each 30 other.

5. An automatic train pipe coupling head 35 operating with a mating coupling head and comprising, in combination, a base, a pair of vertically spaced laterally flaring guiding prongs on one side of the vertical center line of said base, a guiding arm on the opposite side of said center line, guiding walls lying between the upper and lower edges of said prongs, and a seat on said walls for receiving said guiding arm, the guiding 40 arms of mating coupling heads cooperating with the prongs thereof for aligning said heads.

6. An automatic train pipe coupling head 45 operating with a mating coupling head and comprising in combination a base, a guiding member above the horizontal center line of said base and to one side of the vertical line of the base, a guiding prong on the opposite side of said horizontal center line and having a part adapted primarily to guide said head in the early stages 50 of coupling under conditions of extreme disalignment, a wall between said member and said prong and having a seat, and a third guiding part, the guiding member, guiding prong and wall of mating coupling heads cooperating with the third 55 guiding part of such mating heads for aligning the same during coupling operation.

7. An automatic train pipe coupling head 60 operating with a mating coupling head and comprising in combination a base, a pair of vertically spaced forwardly extending outwardly and vertically flaring guides positioned both on one side of the vertical center line of said base, a funnel member integral with said guides and having at its apex an annular seat, and an arm extending 65 away from one side of said base and having a partly spherical portion, the partly spherical portions of mating coupling heads being adapted to co-operate with said guides and said funnel of said heads to align the same and to rest in said 70 seat of a mating head when coupled.

JOSEPH ROBINSON.
